POLYMERIZATION OF HYDROCARBON OILS

Rudolph C. Osterstrom, Chicago, Ill., assignor to
The Pure Oil Company, Chicago, Ill., a corpora-
tion of Ohio

Application April 26, 1930, Serial No. 447,532

5 Claims. (Cl. 196—147)

This invention relates to the art of removing 5
gum-forming and color-imparting bodies from
cracked petroleum distillates. Petroleum distil-
lates obtained particularly from high tempera-
ture or vapor phase cracking systems, contain un-
saturated compounds in the form of undesirable
diolefines which, if permitted to remain in the
distillates, promote or result in the formation of
the gum and color compounds when the distillates
10 are stored and exposed to either air or light.
Such compounds are highly undesirable in motor
fuels particularly and the removal thereof is nec-
essary to permit the distillates to be used com-
mercially. These gums likewise form in cracked
15 distillates produced by other refining systems
than the vapor phase system and the present in-
vention is directed to the treatment of cracked
petroleum distillates or other similar hydrocar-
bon oils to remove therefrom in an effective man-
ner the objectionable hydrocarbons which
20 produce resinous compounds through oxidation and
which tend to impair the desired commercial
color thereof.

For a further understanding of the invention
25 reference is to be had to the following description
and the accompanying drawings wherein:

Figure 1 discloses diagrammatically apparatus
used in carrying the invention into operation, and
Figure 2 is a modification thereof.

Referring more particularly to the accompany-
30 ing drawings, the numeral 1 designates a tank in
which is contained the freshly cracked distillate
which is to be treated in accordance with the
present invention. This distillate consists ordi-
narily of hydrocarbon oils produced by cracking
35 processes and which have the boiling range of ordi-
nary gasoline. These distillates, particularly
distillates obtained by vapor phase cracking, con-
tain highly reactive compounds in the form of
diolefines or other similar types of unsaturated
40 hydrocarbons which are readily attacked by air
and light and form high boiling hydrocarbons of
a resinous character which are ordinarily known
as "gums". These gums possess a highly complex
molecular formation and are thought to be pro-
45 duced in cracked gasolines by the union of cer-
tain types of unsaturated compounds with oxy-
gen. These gums or polymers, however, are read-
ily recognized by their high boiling range which
50 is considerably above that which the distillates
possessed when originally produced or stored.
This indicates that the gums are formed in stored
cracked distillates and effective removal thereof
is required to render such distillates suitable for
55 use as motor fuels, since the presence of such

gums or polymers in a motor fuel oil produce a
highly objectionable condition in the commercial
utilization of such oils in internal combustion en-
gines. It is therefore to an effective and substan-
tially complete removal of these objectionable 5
compounds from cracked distillates that the pres-
ent invention is directed.

Leading from the tank 1 is a pipe line 2 which
enters the suction side of a high pressure pump
3. A pipe 4 leads from the discharge side of the 10
pump 3 to a pipe still 5 in which is located a coil
6. The pipe still comprises the usual wall struc-
ture in which is located a bridge 7 and one or
more burners 8. The oil or distillate to be treat-
ed is forced by the pump or pumps 3 through 15
the pipe line 4 to the coil 6 which is located within
the still and is subjected to the relatively high
temperatures therein prevailing. While in the
coil 6 in a preferred method of operation the dis-
tillate under treatment is maintained under su- 20
per-atmospheric pressures varying between 600
pounds and 1000 pounds per square inch and dur-
ing the passage of the distillate through the coil
6 the temperature of the still is so regulated that
the distillate will attain a treating temperature 25
varying between 500° F. and 600° F. The rate of
flow of the distillate through the coil 6 is subject
to variation, depending upon the nature and de-
gree of treatment required on the part of the
distillates so handled. For example, a vapor 30
phase cracked distillate, which possesses a larger
amount of objectionable unsaturated compounds
than a liquid phase cracked distillate, is main-
tained in the polymerization zone, produced by
the coil 6, for a greater period of time than said 35
liquid phase cracked distillate which, as previous-
ly stated, does not require the same degree of
treatment as the vapor phase product since it
contains smaller percentages of the gum-forming
compounds. Therefore, the oils or distillates so 40
treated may be maintained in the polymerization
zone for periods of time varying between a few
seconds and fifteen or more minutes. In the
polymerization zone the distillates are kept in
the liquid phase, since the pressures utilized are 45
ordinarily more than sufficient to overcome va-
porization of the oils comprising said distillates
at the temperature specified. By thus subjecting
the distillates to the specified conditions of pres-
sure, temperature and time, usually without the 50
employment of a catalyst, complete and effective
polymerization of the objectionable gum produc-
ing compounds takes place so that the oils will
contain high boiling compounds which possess
boiling points materially higher than the oils or- 55

dinarily introduced into the polymerizing zone by the pump 3.

From the coil 6 the oils pass directly while in the liquid phase and under pressure into a container 9 which contains in the base thereof a bed 10 of fuller's earth or its equivalent. The oils are forced through this bed of fuller's earth for the purpose of removing therefrom compounds which possess an undesired color. In this manner 10 the system provides for removing from the distillates or oils treated not only the gum-forming compounds but also those compounds which tend to discolor the same. During their passage through the fuller's earth bed maintained in the 15 container 9 the oils are held substantially in the liquid phase by the employment of super-atmospheric pressures.

After passing through the bed of fuller's earth, the oils leave the container 9 by way of the pipe 11 and thence through an orifice meter or 20 pressure reducing valve 12 which is situated immediately adjacent to a standard fractionating tower 13. By reason of the treatment above described there is formed in the oils as high boiling 25 compounds the objectionable gums or color-producing substances. By ordinary careful fractionation in the tower 13, these high boiling compounds are collected in the bottom of said tower and removed by way of the valved outlet line 14. 30 The desired oils of proper boiling range pass overhead as vapors from the tower 13 by way of the outlet line 15. These vaporized oils are condensed in the condenser 16 and are collected as finished motor fuel oils in the tank 17. By removing the 35 polymerized compounds from these oils the latter may be kept indefinitely under usual conditions of storage and handling without liability of any appreciable further gum formation therein. If desired, a valved gas inlet line 18 may be connected with the pipe line 2 for the purpose of introducing regulated quantities of so-called "fixed gas" obtained from oil cracking systems into the polymerizing zone together with the distillates obtained from the tank 1. It has been found that 40 when fixed gases produced by pyrogenesis from high boiling oils, are subjected to the conditions of temperature, pressure and time prevailing in the treating coil 6 such gases polymerize to form additive compounds of higher molecular weights 45 and which may be subsequently recovered in high percentages as motor fuel distillate. This fixed or permanent gas may or may not be introduced into the system and does not effect the general operation above described.

50 I have found that substantially the full desired degumming effect is obtained by virtue of the high pressures and high temperatures employed with the proper time factor, and that while no material decolorization is obtainable in the coil 6, the clay bed 10, when disposed as specified, produces the desired decolorizing effect.

In the form of the invention disclosed in Figure 2, the polymer-containing vapors are passed from the polymerizing zone 6 of the still 5 directly into a fractionating tower 13a, pressure being relieved by means of the valve 12a. In the tower 13a the light vaporized oils of desired boiling point pass overhead by way of the line 15, the condenser 16 and into the storage tank 17. The oils which 55 pass through the line 15 are of desired color and require no treatment for decolorization purposes. The polymerized oils of high boiling point are removed through the line 14. In the tower 13a, however, I remove near the bottom thereof, a condensate which, while possessing a boiling point

somewhat higher than that discharged through the line 15, is yet within the permissible limits of a motor fuel distillate. This cut or condensate which is removed from the tower 13a by way of the outlet line 18 bears color producing compounds which require additional treatment to render the same water-white and of desired commercial color. In the apparatus shown in Figure 1, the decolorization of this cut is secured by means of the fuller's earth bed 10, but in the form 10 of the invention shown in Figure 2, the oils are fractionally condensed to segregate fraction which contains the color producing compounds and hence it is that fraction particularly which requires special decolorizing treatment. If desired, this fraction could also be passed through a bed of fuller's earth but I have found it advisable to use small quantities of sulphuric acid. This acid is withdrawn from the tank 19 and mixed with the condensate flowing through the 20 line 18, a complete mixing of the acid with the oils taking place in the continuous treater tanks 20. The acid is finally neutralized with caustic and the decolorized oils are transmitted to a storage tank 21.

It will be noted that in the operation of the tower 9 the oils under treatment are in the liquid phase, and these oils exercise a solvent action on the gums or polymers which adhere to the fuller's earth particles contained in the bed 10, thus washing the polymers from the fuller's earth and providing for sustained use of the earth without replenishment or substitution.

The system has the advantage of being far more economical than other polymerization systems heretofore employed for this purpose. This is accomplished by the use of but a limited consumption of clay and the manner of handling of the polymers. Gum polymerization takes place in the coil 6 without the aid of a catalyst such as fuller's earth and the only fuller's earth utilized is that which is contained in the bed 10, and this is subject to a slow rate of deterioration for the reason that the principal reactions are effective in the tube still without the aid of clay. Moreover, the fractionation step provided by the tower 13 provides for the effective removal of the treated gasoline fraction from the polymerized compounds, permitting such latter undesirable compounds to be withdrawn from the bottom of the 50 tower free from gasoline fractions, hence re-running of the polymer fraction is eliminated. Further, the system has the advantage of operating without mechanical difficulties which occur when fuller's earth is forced with the oils to be treated through a tube still. In such an operation the fuller's earth tends to produce erosion of the metal parts with which it contacts sharply with the result that there is considerable replacement of worn parts in such systems and which will not 55 be present in the apparatus above described.

What is claimed is:

1. The method of removing gum-forming and color-imparting bodies from cracked petroleum distillates, which comprises continuously passing such oils in an elongated stream of restricted cross-sectional area through a heating zone wherein such oils are heated to a temperature varying between 500° F. and 600° F., maintaining the oils while passing through said zone under pressures varying between 600 pounds and 1000 pounds per square inch to prevent the vaporization of said oils while the latter are in said heating zone, removing the oils from the heating zone after a desired period of retention 75

therein and passing said oils while in the liquid phase into decolorizing contact with fuller's earth, relieving the pressure on the oils following contact with the fuller's earth to permit of the substantial vaporization of the oils, and fractionating the vaporized oils to remove therefrom the objectionable high boiling polymerized compounds.

2. The method of polymerizing hydrocarbon products obtained from cracking operations, which comprises heating a mixture consisting of a cracked motor fuel distillate and fixed hydrocarbon gas to a temperature varying between 500° F. and 600° F. while said mixture is maintained under super-atmospheric pressures varying between 600 pounds and 1,000 pounds per square inch, then removing the mixture from said zone after a desired period of retention therein and passing said mixture in a substantially liquid state through a bed of fuller's earth, removing the pressure on said mixture to reduce the latter to a substantially vaporous state, and then fractionating the vaporized oils to remove therefrom the undesired high boiling polymerized compounds.

3. The method of accelerating the polymerizing of gum-forming and color-imparting bodies in low-boiling cracked petroleum oils, which comprises continually passing such oils admixed with fixed gas in an elongated stream of restricted cross-sectional area through a heating zone wherein said oils and gases are heated to a temperature of the order of approximately 600° F., maintaining the oils and gases while passing through said zone under pressures varying between 600 pounds and 1000 pounds per square inch, maintaining the oils and gases in said heating zone for a sufficient period of time to effect the desired polymerization thereof, removing the heated products from said heating zone and, without releasing pressure, bringing the same into direct contact with a decolorizing adsorbent earth, relieving the pressure on said products following contact with the decolorizing material, and fractionating said products to separate the same into high boiling and low boiling compounds.

4. The method of removing gum-forming and color-imparting bodies from cracked gasoline-containing distillate which comprises heating such a distillate in the absence of catalysts and of added hydrogen to a temperature considerably in excess of the normal vaporizing temperature but below a temperature sufficiently high to re-crack such distillate, while maintaining said distillate under pressures varying between 600 and 1000 pounds per square inch, removing the distillate from the heating zone after the desired period of retention therein and, without substantial pressure reduction and while the distillate is essentially in the liquid phase, passing said distillate before separation of vapors through a bed of decolorizing adsorbent earth, relieving the pressure on the distillate following contact with said adsorbent to reduce the distillate to a substantially vaporous state, fractionating the vaporized distillate to remove therefrom the undesired high-boiling polymerized compounds, and condensing and recovering the treated distillate.

5. The method of removing gum-forming and color imparting bodies from cracked gasoline-containing distillate which comprises heating such a distillate in the absence of catalysts and of added hydrogen to a temperature in excess of 500° F. but below a temperature sufficiently high to re-crack such distillate, while maintaining said distillate under pressures varying between 600 and 1000 pounds per square inch, removing the distillate from the heating zone after the desired period of retention therein and, without substantial pressure reduction and while the distillate is essentially in the liquid phase, passing said distillate before separation of vapors through a bed of decolorizing adsorbent earth, relieving the pressure on the distillate following contact with said adsorbent to reduce the distillate to a substantially vaporous state, fractionating the vaporized distillate to remove therefrom the undesired high-boiling polymerized compounds, and condensing and recovering the treated distillate.

RUDOLPH C. OSTERSTROM.
